P. RAUCHFUSS

ELECTRIC HEATER

Filed Nov. 1, 1922

Inventor:
Paul Rauchfuss;
by *Alfred S. Davis*
His Attorney.

UNITED STATES PATENT OFFICE.

PAUL, RAUCHFUSS, OF BERLIN, GERMANY, ASSIGNOR TO GENERAL ELECTRIC COMPANY, A CORPORATION OF NEW YORK.

ELECTRIC HEATER.

Application filed November 1, 1922. Serial No. 598,401.

To all whom it may concern:

Be it known that I, PAUL RAUCHFUSS, a citizen of the German Realm, residing at the city of Berlin, Germany, have invented certain new and useful Improvements in Electric Heaters, of which the following is a specification.

This invention relates to electric heaters, more particularly to heaters in which the liquid itself forms the heating resistance, such, for example, as used in steam boilers, and has for its object the provision of means whereby such heaters may be regulated in a simple, reliable and efficient manner.

The regulation of the consumption of energy in steam boilers heated electrically on the electrode principle is effected by varying the path of the liquid between the electrodes. This variation of the path of the liquid may be accomplished in the most widely different ways, either by varying the level of the water in the boiler, or by adjusting the electrodes with relation to each other, or by adjusting insulating tubes, or by several of these methods of adjustment in common.

More specifically the present invention relates to the regulation of the consumption of energy in steam boilers electrically heated on the electrode principle, having stationary electrodes and adjustable insulating tubes. In one form of my invention the insulating tubes, which are adapted to be adjusted in the direction of their longitudinal axis, are inserted at their upper ends in stationary insulating tubes which gradually become narrower and which are arranged above the said upper ends. By means of this arrangement the resistance of the passage for the liquid may be very gradually increased by lifting the lower insulating tubes, an extremely fine regulation of the consumption of energy thus being obtained. The movable insulating tubes may be to advantage arranged on a common cross-piece and this may be lifted and lowered from below from a regulating rod, for example by means of worms and gear wheels.

The drawing shows one illustrative embodiment of the invention in longitudinal section.

Referring to the drawing, *a* indicates the electrodes located in the boiler *b*. They are carried on the inner end of current supply

bars or rods *c* which project outside the boiler *b* through suitable insulators *1*. The electrodes are stationary, being positioned so that they are submerged to the desired extent in the liquid in the boiler. The electrodes are in a well known manner surrounded by insulating members or tubes *d*, the upper ends of which may be inserted in insulating members or tubes *e* of conical form which broaden gradually in a downward direction. These insulating tubes *e* are arranged in a stationary manner on a suitable holder *f*, while the insulating tubes *d* rest on a common cross piece *g* and may be lifted and lowered with the latter from the regulating-rod *l*. By reason of the annular space between the insulating tubes *d* and *e*, which space, in consequence of the conical shape of the insulating tube *e*, narrows gradually as the insulating tubes *d* rise, the resistance of the liquid path becomes greater gradually and accordingly regulates very gradually the consumption of energy.

What I claim as new and desire to secure by Letters Patent of the United States, is:—

1. An electric heater for liquids comprising a plurality of electrodes immersed in the liquid to be heated, cooperating insulating members surrounding one of said electrodes, said insulating members telescoping one within the other, and means for adjusting said members axially with relation to each other so as to vary the liquid path between said electrodes.

2. An electric heater for liquids comprising a plurality of electrodes immersed in the liquid to be heated, a pair of tubular insulating members surrounding each of said electrodes, one of the members in each pair being conical, and means for adjusting the members in each pair with relation to each other so as to vary the liquid path between said electrodes.

3. An electric heater for liquids comprising a plurality of electrodes immersed in the liquid to be heated, stationary conical tubular insulating members surrounding said electrodes, movable insulating tubes surrounding said electrodes and cooperating with said stationary insulating members, and means for adjusting said insulating tubes so as to vary the liquid path between said electrodes.

4. An electric heater for liquids compris-

ing a plurality of electrodes immersed in the liquid to be heated, stationary conical tubular insulating members surrounding said electrodes, movable insulating tubes 5 surrounding said electrodes and inserted in said conical members, a common support for said insulating tubes, and means for moving said support so as to adjust said insulating tubes along their longitudinal axes with relation to said conical members and vary the liquid path between said electrodes.

In witness whereof I have hereunto set my hand this 9th day of October, 1922.

PAUL RAUCHFUSS.
